UNITED STATES PATENT OFFICE.

CHARLES GILBERT HAWLEY, OF CHICAGO, ILLINOIS, ASSIGNOR TO BAKER WHEEL AND RIM COMPANY, OF CHICAGO, ILLINOIS, A CORPORATION OF ILLINOIS.

METHOD AND MEANS FOR FERRULING WOODEN SPOKES.

Application filed August 27, 1920. Serial No. 406,289.

To all whom it may concern:

Be it known that I, CHARLES GILBERT HAWLEY, a citizen of the United States, and a resident of Chicago, county of Cook, and State of Illinois, have invented certain new and useful Improvements in and for Methods and Means for Ferruling Wooden Spokes, of which the following is a specification.

My invention relates generally to the production of wooden members having ferruled ends, but in some of its aspects relates more particularly to the production of wooden spokes for use in vehicle wheels.

The general object of my invention is to provide a method and means of ferruling wooden members whereby an exceptionally strong and durable wooden member can be provided.

It is also an object of my invention to provide a method and means for producing wooden spokes for use in vehicle wheels, but more particularly automobile wheels which shall lend themselves to the production of an exceptionally strong, light, resilient, durable and safe wheel.

It is also an object of my invention to provide a method and means for producing wooden spoke members whereby the assembly of the spoke and metallic parts is facilitated, a much stronger and better wheel produced, and whereby the cost of production can be decreased.

It is a particular object of my invention to provide a wooden spoke member, and a method of producing the same, which shall be especially adapted to the manufacture of wheels wherein the usual felly is dispensed with, to which type of wheel I have heretofore applied the term "semi-wood wheel."

My invention consists generally in the steps, acts, and stated sequence thereof, in the means and also in the article of manufacture resulting therefrom, whereby the above named objects, together with others that will appear hereinafter, are attainable; and my invention will be more readily understood by reference to the accompanying drawings, which illustrate what I consider at the present time to be the preferred embodiment thereof.

In said drawings:

Fig. 1, is a somewhat diagrammatic view

showing one of the steps in the manufacture of a wooden spoke to which a metal ferrule is to be applied.

Fig. 2 is a view similar to Fig. 1, but illustrating an advanced step.

Fig. 3, is a view similar to Fig. 2, but illustrating the ferrule applied and the parts separated.

Fig. 4 is an enlarged detail view of the ferruled end of the spoke during that step of the operation depicted in Fig. 2.

Fig. 5 is a detail sectional view of a modification of my invention.

Fig. 6 is a detail sectional view of a still further modification.

Figs. 7 and 8 illustrate ferruled wooden members of different kinds embodying my invention.

Fig. 9 is a view, partially in elevation and partly in section, of mechanism used in practicing my invention.

Figs. 10 and 11 are detail views illustrating the manufacture of modified forms of spoke ends embodying my invention; and

Figs. 12 and 13 are respectively detail views showing the application of the spoke ends of Figs. 10 and 11 to or their association with the metallic bands of automobile wheels.

Inasmuch as wooden ferrule members embodying my invention are particularly adapted for use with and are of especial value as applied to the spokes of automobile wheels, I shall describe my invention with particular reference to such use, but this, it should be understood, is by way of illustration and not by way of limitation.

An automobile wheel of the type referred to is composed of a plurality of wooden spoke members usually provided with mitered butt portions so that when associated together a solid central or hub portion is provided.

Much of the stability of the wheel is dependent upon the proper formation of this central wooden or hub part of the wheel and the accurate fitting thereof both initially and thereafter in use, is of vital importance. So also in the manufacture of the so-called semi-wood wheels in which the usual felly is omitted and the tire or rim carrying band is positioned directly upon or secured to the spoke ends, the form, sta-

bility and characteristics of the spoke ends become of vital importance. This will be readily understood when it is recalled that in wheels of this character a fastening device, such as a bolt, may pierce the spoke end and in any event the spoke ends in use are subjected to the direct action of the load.

I have provided a method and means of 10 conditioning wooden spokes whereby they are adapted admirably to meet the exacting requirements of a semi-wood spoke.

Referring again to the drawings, 1, represents a wooden spoke which as here shown 15 is provided with a cylindrical outer portion 2 and a butt portion 3, which is provided or formed with mitered faces 4. It will be understood that in the formation of the wheel a full complement of wooden spokes 1 will be arranged in radial form, the butts 3 forming the all wood center. Because of the necessity of a plurality of such spokes co-acting it is essential that the size and mitered form of the butts be accurate and uniform. Because of the fact 25 that the outer ends of the spokes must engage and be encompassed by a band it is also essential that the length of the various spokes be accurately and uniformly fixed. 30 These desirable characteristics are imparted to the spoke and at the same time a ferrule is secured to the outer end thereof. To this end I place a wooden spoke, which is generally cut or formed substantially to size 35 and with the desired shaped butt portion. The various spoke members will be found in practice to vary somewhat in size, some being larger and longer than others. I provide a die member 5 having a die opening 40 6 therein which is substantially the diameter of the cylindrical end portion 2 of the spoke. Therein I place a metallic band or a ferrule 8. Behind the ferrule I arrange a plunger 9, the purpose of which will 45 shortly be described. The die opening 6 is provided with a bell-shaped mouth 10 and the ferrule is preferably beveled as indicated at 11. Spaced from the die 5, which may be considered as a stationary die, will 50 be found a movable die 12 which is provided with a die opening 13 having inclined faces 14 which diverge at precisely the angle desired in the spoke butt. Means are provided for forcibly moving the die 12 toward 55 the die 5 and in the course of such movement the wooden spoke 1 is moved longitudinally toward the die 5, the end portion 2 thereof entering the bell-shaped mouth of the die, being compressed thereby, 60 and upon further movement entering the ferrule 8 so that eventually the end face 15 of the spoke abuts against the plunger 9. By fixing the extent of the movable die 12 it is obvious that the length of the wooden spoke 1 is accurately fixed. Also that

when an oversize spoke is acted upon it is compressed and very nicely and accurately sized and shaped. The end of the spoke upon which the metal ferrule has been forced is obviously compressed and that portion of the spoke is made denser and more resistant to and hence better adapted to withstand the direct action of the load imposed thereon in a wheel. The ferrule 70 obviously is firmly fixed on the spoke and becomes, in effect, an inseparable part thereof. After the spoke has been thus acted upon as is shown in Figs. 2 and 3 the die 12 is withdrawn and the plunger 9 actuated to force the spoke end out of the die 5 in 80 which it was tightly held by the compressive action before referred to.

Obviously members other than wooden spokes may be conditioned in like manner and in Fig. 7, 16 represents a wooden handle-like member provided with a ferrule 17. So in Fig. 8, 18 is a still different form of wooden handle member provided with a ferrule 19.

In Fig. 5, a slightly different form of my 90 invention is shown. Instead of an immovable die 5 for acting upon the spoke, I provide separable jaw members 20 and 21, which are provided with recesses or openings forming the die opening 22 and which have bell-shaped entrant portions as indicated at 23.

These movable die members 20 and 21 are vertically separated to permit insertion of the ferrule or band 24. They are then closed to the full line position shown in Fig. 5 and the spoke end forced into place. To release the stake end with the metallic ferrule attached thereto the die members 20 and 21 are vertically separated. This ferruled member differs from the one first described in that the ferrule is not entirely flush with the adjacent part of the wooden member.

In Fig. 6 a slightly different form of my 110 invention is shown wherein 25 and 26 are separable die members, 27 the ferrule and 28 the wooden member to which the ferrule is to be applied. The ferrule is originally of a size substantially equal to that of the member 28 and by bringing the die members 115 25 and 26 together the same is upset or compressed upon and around the end of the member 28 thus packing or condensing the wood and firmly securing the ferrule in place.

In Fig. 9 will be found mechanism for actuating the die parts of that form of my invention shown in Figs. 1 to 4 inclusive, and to which I have applied like reference characters. The movable die member 12 it 125 will be seen has a stem or guide portion 29 which operates in a guide block 30. The stem or guide rod 29, in turn, is connected to an arm or link 31 which is connected to an eccentric or crank pin 32. Obviously ro-

tation of the crank pin 32 around the center or shaft 33 will impart a reciprocatory movement to the stem 29 and die carried thereby.

5. In Fig. 10 will be found a modification wherein 34 represents a die similar to the die 5 but having a curved bottom to the die opening indicated at 35 whereby the end may be curved to the arc of a circle corresponding to the form of a metal band with which it is to be used in the production of a wheel.

In Fig. 12 will be found a spoke end associated with a metallic band 36 having a conical flange 37 thereon adapted to receive and support a demountable rim. For the purpose of actuating the lug or clamp that is used in conjunction with the demountable rim, not shown, a bolt 38 is passed through 20 the outer ferruled end of the spoke and through the dependent flange portion 36' of the band 36. A recess or opening 39 is provided in the band 36 into which a portion of the bolt head 40 projects. Because 25 of the dense character of the ferruled end of the spoke it serves admirably to receive and hold the bolt 38 and also to withstand any and all loads imposed thereon in the use of the wheel.

30 The wheel construction shown in Fig. 12 is adapted to receive a demountable rim whereas the wheel construction shown in Fig. 13 is one wherein a detachable side flange is provided and the tire secured directly on the band or tire holding rim 41. The end of the spoke is provided with a tenon or central projection 42 which enters a hole 43 in the band 41. The ferrule 44 can be placed upon the spoke in any of the 40 ways before described. The ease with which the metallic ferrule can be affixed and the tenon 42 conditioned is well shown in Fig. 11 wherein like reference characters are applied to the spoke as in Fig. 13 and wherein 45 45 represents the die. Obviously by forcing the spoke into the die 45 the spoke can be very quickly and accurately sized, shaped and the end thereof compressed better to withstand conditions of use.

50 The many advantages of my invention will be understood by those skilled in this art without further comment.

I claim:—

1. The herein described method of operating upon wooden spokes having mitered butt ends which consists in simultaneously compressing the fibres of both ends of said spoke and at the same time firmly securing a ferrule upon that end of the spoke opposite the mitered butt end.

2. The herein described method of operating upon wooden spokes having mitered butt ends which consists in simultaneously compressing the fibres of both ends of said spokes, and at the same time sizing the

mitered butt end and firmly securing a ferrule upon that end of the spoke opposite the mitered butt end.

3. The herein described method of sizing and ferruling wooden spokes that consists 70 in longitudinally aligning a wooden spoke and an undersize ferrule, and by forces acting longitudinally of the parts compressing one end of the spoke and forcing the ferrule thereon and compressing and sizing the butt 75 portion.

4. An apparatus for operating upon wooden spokes having mitered butt ends, comprising in combination means for holding, 80 a ferrule, means for receiving and engaging the mitered butt end of a spoke, and means for producing a relative endwise movement between said ferrule holding means and said butt end receiving and engaging means, said two last mentioned 85 means acting during said relative movement to compress the mitered butt end to size and to tightly secure a ferrule around the other end of the spoke.

5. The herein described means of ferruling and sizing wooden spokes embodying 90 therein means for holding a ferrule, said means having an outwardly flaring die opening, means adapted to engage the butt of and hold a wooden spoke, and means 95 for causing the approach of the ferrule holding means, and the butt spoke engaging means, whereby the ferrule is placed around and tightly secured to one end of the spoke and the mitered butt sized.

6. The herein described means of ferruling and sizing wooden spokes embodying 100 therein means for holding a ferrule, means adapted to engage the butt of and hold a wooden spoke, means for causing the approach of the ferrule holding means, and the butt spoke engaging means, whereby the ferrule is placed around and tightly secured to one end of the spoke and the mitered butt is sized, and means for separating 105 the ferruled spoke from the holding means.

7. An apparatus for operating upon 110 wooden spokes having mitered butt ends, comprising in combination, means for holding a ferrule, means for receiving and engaging the mitered butt end of a spoke, means for producing a relative endwise movement between said ferrule holding means and said butt end receiving means, 115 said two last mentioned means acting during said relative movement to compress the butt end to size and to tightly secure a ferrule around the other end of the spoke, and means for removing the ferruled and sized spoke from said two last mentioned means, said spoke removing means including a movable plunger positioned in said ferrule holding means.

8. As an article of manufacture a wooden 120

spoke having a compressed end portion and a ferrule held thereon by the expansive action of said compressed portion, and having a compressively sized butt portion.

5 9. As an article of manufacture a wooden spoke member having compressively sized and shaped butt and opposite end portions.

10. As an article of manufacture a wooden

spoke, for semi-wood wheels, having a compressed end portion provided with a ferrule and a bolt piercing the compressed ferruled end portion thereof.

In testimony whereof, I have hereunto set my hand this 5th day of August, 1920.

CHARLES GILBERT HAWLEY.
